BOTTLE

Edward H. Lawton, Toledo, Ohio, assignor to Owens-Illinois, Inc., Toledo, Ohio, a corporation of Ohio

Filed Dec. 11, 1968, Ser. No. 14,918

Term of patent 14 years

Int. Cl. D9—01

U.S. Cl. D9—140

I claim:

The ornamental design for a bottle, as shown and described.
